UNITED STATES PATENT OFFICE.

TERANCE SCULLIN AND SOREN ROBERTSON SKOV, OF CLEVELAND, OHIO.

MEANS FOR OPERATING CAR-DOORS.

1,071,469.

Specification of Letters Patent. Patented Aug. 26, 1913.

Application filed January 26, 1912. Serial No. 673,645.

To all whom it may concern:

Be it known that we, TERANCE SCULLIN and SOREN ROBERTSON SKOV, citizens of the United States of America, residing at Cleveland, in the county of Cuyahoga and State of Ohio, have invented certain new and useful Improvements in Means for Operating Car-Doors, of which the following is a specification.

10 In our application for Letters Patent of the United States executed of even date, we disclose means for operating car doors especially adapted for operation from the rear platform, whereas in the present application, we disclose preferred means for operating the car doors from the front platform.

The broad feature of our invention, namely the slip joint between the door and the operating mechanism to permit said mechanism to continue its movement when the door meets an obstruction, and means for storing energy when said mechanism is operated independently of the door to close the door after the obstruction is removed, is not claimed in this application serial No. 673,646, filed January 26, 1912, as claims for such broad invention are made in the companion application.

30 In the drawing, Figure 1 is a side elevation of a car, parts being broken away, illustrating our invention; Fig. 2 is a top plan view of the door tracks, the doors and parts of the car structure in section, and Fig. 3 is an end elevation showing the relative positions of the pinion, cylinder, the doors and the track, parts being in section.

The numeral 1 designates the car broken away, there being a panel or partition 2 and 3 forming the outer wall of the car at each side of the door opening.

4 is the outer door track and 5 the inner door track, which extend across the door opening and between the side of the car and the panel or partition 2 and 3, as clearly shown in Fig. 2.

6 and 7 are the outer doors and 9 and 8 are the inner doors; the outer doors being provided with a weather strip 10, clearly shown in Fig. 2. The inner doors 9 and 8 are suspended from the track 5 by means of the hanger brackets 11 and 12, while the outer doors 6 and 7 are suspended from the track 4 by means of the hangers 13 and 14, all of said hangers being provided with suitable curved wheels adapted to run on

the door tracks. The outer doors are each provided with a second hanger carrying a curved roller adapted to move on the door track.

15 are stationary rack bars secured to the car structure.

16 are gear wheels journaled upon the inner door brackets 11, 12, respectively, as clearly seen in the drawing.

17 is a track attached to the outer wall of the door casing, on which the racks 18 and 19 are slidably mounted by means of the guides 20, 21 22 and 23.

24 is a rod positioned between the guides 21 and 22 around which is coiled a spring 26, one end of which presses against the hanger 14, while the other end is seated against the abutment 27, which is a part of the rack at 21. The parts 25, 22, 23, 13 and 27 on the left hand of Fig. 1 are duplicates of those first described, therefore, further description of them is unnecessary.

It will be noted that one end of the rod 24 is screw-threaded in a suitable abutment socket on the guide 20 while the other end is mounted in the abutment 27, there being a loop "A" on bracket 14 sliding over rods 24 and 25 and permitting the doors to have relative movement by reason of the compressed springs 26 over rods 24 and 25.

29 is an extension from the bracket 11, which is adapted to be connected to the piston rod 30 and locked thereto by means of the nuts 31, whereby the inner door is positively locked to the piston rod.

32 is a piston secured to the rod, said rod and piston being inclosed in the operating cylinder 33, which is provided with an inlet 34 and an outlet 35, the cylinder being divided at the middle by a wall, thus forming two independent cylinders and being connected to the air supply of the car by suitable piping and valves.

Assuming that the doors are closed, as shown in Fig. 1, air is admitted to the cylinder 33 through the inlet 34 against the piston 32, whereby the piston 32 is moved with its rod 30 toward the outlet 35. In this movement, the rod carries with it the extension 29 and the door bracket 11. As the bracket 11 and its extension are moved backward, the pinion 16 begins to rotate and acts upon rack 18 and propels it with a velocity equal to twice that of the door bracket 11, inasmuch as the rack 15 is stationary. The motion of the rack 18 is transmitted to the

outer door 7 through the rack 18 and through the bracket 14 and the movement of the doors is continued until they have reached their proper positions between the 5 inner wall of the car and the outer wall or panel 3, leaving a free unobstructed opening for passengers entering and leaving the car.

The closing motions are a reversal of those just recited, unless an object, for instance a 10 person, is in the path of the door 7 as it is being closed. In such contingency, the rack 18 would continue to slide on the track 17 until it reaches its normal closed position; the loop A on bracket 14 would slide over 15 rod 24 thereby compressing the spring 26 until the object is removed from the path of the door, when the stored energy of the spring 26 would immediately propel the door 7 to its usual closed position. While 20 in the description of the operation, we have referred only to the doors 7 and 9, it will be understood that the same description of operations applies to the doors 6 and 8, simultaneous with 7 and 9. It will also be understood that if only two doors are required 25 on a car, one-half the structure illustrated in Fig. 1 need only be used.

We claim:—

1. The combination with a pair of sliding doors moving in the same direction, of an operating cylinder, a piston and piston rod mounted in said cylinder, means connecting one of said doors to said piston rod for positive movement therewith in both directions, means operated by said door for moving the other door in the same direction simultaneously with the first named door.

2. The combination with a pair of sliding doors moving in the same direction, of an operating cylinder, a piston and piston rod mounted in said cylinder means connecting

one of said doors to said piston rod for positive movement therewith in both directions, means operated by said door for moving the other door in the same direction, but at a 15 different rate of speed.

3. The combination with a pair of sliding doors moving in the same direction, of an operating cylinder, a piston and piston rod mounted in said cylinder, a bracket extending from one of said doors and rigidly connected to said piston rod, a stationary rack, a pinion journaled on said door hanger, a 50 slidably mounted rack, a rod mounted on abutments of said rack, and a spring coiled 55 around said rod.

4. In a door operating mechanism, the combination with a sliding door, of a bracket secured thereto, a stationary rack bar, a pinion journaled on the said bracket 60 and adapted to engage said stationary rack bar, a slidably mounted rack bar, an abutment on said rack, a second sliding door movable in the same direction as the first-named sliding door, a bracket extending 65 from said second door, a rod rigidly secured at both ends to said sliding rack and a loop over said rod, a spring coiled around said rod between the loop and rack, said sliding rack connected to the bracket of the second-named sliding door and adapted to engage the said pinion, whereby movement is transmitted from the first-named door to the second-named door through said sliding rack.

The foregoing specification signed at 75 Cleveland Ohio this 5 day of Jan., 1912.

TERANCE SCULLIN,
SOREN ROBERTSON SKOV.

In presence of—

CHAS. A. D. C. SON,
A. DE CAPUOR.
